UNITED STATES PATENT OFFICE.

JULJA DZIEDZIE, OF DETROIT, MICHIGAN.

FIRE-ALARM-SIGNAL BOOTH.

Application filed May 1, 1920. Serial No. 378,178.

To all whom it may concern:

Be it known that I, JULJA DZIEDZIE, a subject of the Emperor of Austria, residing at Detroit, county of Wayne, and State of Michigan, have invented certain new and useful Improvements in Fire-Alarm-Signal Booths, of which the following is a specification.

This invention relates to improvements in fire alarm signal booths, and its principal object is to provide means whereby a party operating the alarm signal is compelled to remain in the booth, thereby tending to prevent irresponsible false alarms, and further assuring that the party turning the alarm in will be at hand to direct the firemen to the place where the fire exists.

This object is attained by the novel construction and combination of parts herein-described and shown in the accompanying drawings, forming a material part of this invention, and in which—

Figure 1 is a vertical sectional view looking from the interior of the booth towards the door.

Figure 2 is a vertical sectional view taken on line 2—2 of Figure 1.

Figure 3 is a fragmental front elevational view showing the operative parts in another position from that indicated in Figure 2.

Figure 4 is a fragmental view showing the hinge used in the lever construction.

In the drawings, the booth 10, is made sufficiently large to contain a person, the booth being provided with a door 11, connected by the hinges 12, and having a roof 13 to protect the apparatus therein.

The booth may have a seat 14, and is intended to contain signaling apparatuses, such as the telephone 15, used to communicate whatever message may be desired with fire or police stations; a screened window 16 is arranged in the door 11, permitting ventilation and light to enter.

Attached to the inside front edge of the door 11 is a keeper 18, adapted to receive the front end of a bolt 19, the same being slideable in guides 20 attached to the front interior wall of the booth, the bolt having an eye 21 by which it may be drawn. A vertical bar 23 is slidably arranged within guides 24, attached to the booth, the bar being parallel with the front edge of the door adjacent thereto.

The upper end of the bar 23 has an angularly turned arm 25, adapted to form a cir-

cuit between the contact plates 26 when in position, and also has a projection 28, formed upon its extreme lower end, adapted to enter and engage in a transverse slot 29 formed across the upper edge of the bolt 19.

A pin 30 is secured in the upper end of the bar 23 engageable with a transverse slot 31 formed in a horizontal bar 32, movable in guides 33 secured to the booth, the bar 32 being at such height above the top of the door as not to interfere with its action.

A hinged joint 34 allows the opposite end of the bar 32 to pivotally engage with an arm 35, of a bracket 36, secured to the door in such manner that the arm describes a partial circle of which the hinges 12 are the axes, thus, opening or closing the door causes the bar 32 to move longitudinally.

A switch blade 40 is secured to the inner front edge of the door so that when closed it engages with the other part 42 of the switch secured to the booth and from which run wires 43 and 44 from any convenient source of electricity, as the battery 55 whereby the electric lamp 45 is caused to glow.

The device operates as follows:

A person desiring to enter the booth in order to give an alarm, will raise bar 23 by means of its projection 23' extending through a longitudinal slot in the bar in which it travels. This operation will lift pins 28 and 30 on said bar out of the recess 29 and 31 in the bolt 19 and bar 32 respectively so that the bolt 19 can now be unlocked by the proper manipulation of knob 49 or by a suitable key.

As the switch elements 40 and 42 in the interior of the booth are so arranged as to be out of circuit unless the door is fully closed or when the contact plates are connected by arm 25 of bar 23, it will be clear that a person entering the booth and desiring to operate the telephone, will have to lock the door by operating the latch 19 by means of its knob 47 in order to allow pins 28 and 30 of bar 23 to drop back into recesses 29 or 31 respectively to lock the booth and to close contacts 26. As the parts operating the bar 23 on the inside of a door are enclosed in a casing, it will be impossible for any person within the booth after the giving of the alarm and locking himself in for this purpose, to leave the booth, as the door can only be opened from the outside by lifting bar 23, so that the fire department will be able to identify the sender of an alarm and eventually

ally will get without delay the exact location of the fire. In order to ensure a double locking of the device, parts 30 to 36 are provided.

5 Having thus described my invention what I claim as new and desire to secure by Letters Patent of the United States is as follows:

1. A fire alarm booth of the class described comprising a latch, having a recess in its upper edge, a vertical bar forming a circuit closing means, a pin on said vertical bar adapted to engage the recess of said latch, means for lifting said vertical bar out of engagement with said latch to open the circuit, means for lowering said vertical bar from the inside of the booth for locking said latch and closing circuit, and means for preventing the operation of said bar out of its locking position from the inside of the booth.

2. In a booth of the class described the combination of a recessed horizontal latch

adapted to engage a keeper for locking the door of the booth and having a recess in its upper edge, with a vertical sliding bar, a pin on said vertical bar adapted to engage in the recess of said latch, for locking the same in its booth locking position, upon the lowering of said vertical bar, a handle on said vertical bar extending to the outside of said booth and movable within a longitudinal slot in the front wall of said booth for allowing a lifting of said bar from the outside out of engagement with said latch, a circuit closing means on said vertical bar adapted to close a circuit over a telephone when the vertical bar is in its lower locking position, a knob on said latch adapted to be operated from the inside of the booth for locking the same in order to close the signal circuit, and means for preventing an unlocking of the latch from the inside of the booth.

In testimony whereof I have affixed my signature.

JULJA DZIEDZIE.
